FRED A. GERLING, OF BOISE, IDAHO

ROTARY FLUID COMPRESSOR

Application filed August 19, 1930. Serial No. 476,388.

My invention relates to rotary fluid compressors.

An important object of the invention is to provide a machine of the above mentioned character having a high efficiency in operation.

In the accompanying drawings, forming a part of this specification, and in which like numerals are employed to designate like parts throughout the same,

Figure 1 is a side elevation of the machine embodying my invention,

Figure 2 is an end elevation of the same,

Figure 3 is a vertical longitudinal section taken on line 3—3 of Figure 2, showing the rotating unit in the vertical position.

Figure 4 is a similar view, showing the rotating unit disposed at an angle of about 45° from the vertical.

Figure 5 is a transverse section taken on line 5—5 of Figure 3,

Figure 6 is a detailed longitudinal section through the connecting rod,

Figure 7 is a side elevation of the rotary support or frame, and,

Figure 8 is a horizontal section taken on line 8—8 of Figure 5.

In the drawings, wherein for the purpose of illustration, is shown a preferred embodiment of my invention, the numeral 10 designates a pair of standards mounted upon a suitable base 11 and provided at their upper ends with bearings 12, for receiving the horizontal rotatable shaft sections 13 and 14. The machine embodies a rotatable unit, including a pair of cylinders 15, which are rigidly connected with arms 16, the intermediate portions of which are rigidly connected with flanges 17, formed upon sleeves 18. These sleeves are rotatable with the shaft sections 13 and 14.

A pulley 19 may be rigidly mounted upon the shaft section 13 to rotate the unit and may be driven by any suitable means. A hollow annular drum 20 is mounted upon the shaft section 14 to rotate therewith, and is bolted or otherwise rigidly attached to the adjacent sleeve 18, as shown at 21, and this drum is provided upon its outer side with an annular opening 22 in communication with a

stationary annular drum 23, having a sliding gas-tight joint therewith, as shown at 24. An outlet pipe 25 is connected with the stationary drum 23 and may lead to any desired point.

Each cylinder 15 is provided with an inwardly opening check valve 26 and an outwardly opening check valve 27, having connection with a pipe 28, connected with the rotary drum 20 and leading to the interior of the same. The air compressed within each cylinder 15 is thus fed to the rotary drum 20.

Mounted to reciprocate within the cylinder 15 are plungers 29, Figure 5, which are connected by a rigid straight line plunger rod 30, having an intermediate yoke portion 31, including spaced arms 32. This yoke portion and associated elements operates between the flanges 17, and the plunger rod 30 reciprocates during the rotation of the unit, for effecting the movement of the plungers.

Rigidly connected with the cylinders 15, and preferably formed integral therewith, are supporting arms 33, disposed at a right angle to the axes of the cylinders and facing in opposite directions with relation to each other. Bell crank levers 34 and 34' are pivotally mounted upon the outer end of the arms 33, as shown at 35, and these bell crank levers carry weights 36, at their free ends. These bell crank levers have pivotal connection at their opposite free end, as shown at 37, with links 38 and 38'.

The numerals 39 and 39' designate shifting or centralizing levers, extending transversely of the arms or frame connecting the cylinders, and projecting beyond the opposite sides of the frame, as shown. The lever 39 is supported, by the pivot 40, carried by a lug or bracket 41, formed upon the cylinder frame. The lever 39 has its right end, Figure 4, extending for a greater distance beyond the side of the cylinder frame than its left end, as shown. The lever 39' extends transversely of the cylinder frame and is supported by a pivot 42, carried by a lug or bracket 43 secured to the cylinder frame. The left end of the lever 39', Figure 4, extends for a greater distance beyond the side of the cylinder frame than its right end. The

shifting lever 39, see particularly Figure 6, has pivotal connection at 39^a with a link 40^a, the opposite end of which is pivoted at 41^a, with the shifting lever 39'. A pin 42^a is attached to the center of the links 40^a and operates within longitudinal slots 43^a, formed in the sides 32 of the yoke 31. The link 38 is pivotally connected with the long arm of the shifting lever 39, as shown at 44, while the link 38' is pivotally connected with the long arm of the shifting lever 39', as shown at 45.

The numerals 46 and 46' designate actuating levers, pivotally mounted upon the cylinder frame, as shown at 47, near the cylinders. 15 These actuating levers carry weights 48 upon their outer ends. A link 49 is pivotally connected with the actuating lever 46, as shown at 50, and is pivotally connected with the short arm of the shifting lever 39, as shown at 20 51'. In a corresponding manner, a link 51 is pivotally connected with the actuating lever 46', as shown at 52, and is pivotally connected with the short arm of the shifting lever 39', as shown at 25 53. These actuating levers are operated by gravity and act upon the shifting levers 39 to swing their long arms in the same direction.

Weight operated toggle joints 54^a and 54^b are connected with the shifting levers 39 and 39'. The toggle joint connected with the shifting lever 39' embodies a lever 54, the inner end of which is pivoted upon the cylinder frame, as shown at 55. The outer end of the lever 54 has pivotal connection, as shown at 56, with a link 57, which is pivoted to the long arm of the lever 39, as shown at 58. An L-shaped arm 59 is connected with the link 57, by the same pivot or pin 56, and is connected with a brace 60, which brace is connected with the link 57, as shown at 61. The 40 L-shaped arm 59 is in effect rigidly connected with the link 57. The L-shaped arm 59 carries a weight 62 at its outer end. The angular position that the L-shaped arm 59 has, with respect to the link 57, remains fixed. 45 The toggle joint connected with the long arm of the shifting lever 39 is identical with the toggle joint, thus described, and embodies a lever 54', link 57', and L-shaped arm 59'. It is thought to be unnecessary to further describe this identical toggle joint.

Means are provided for opening or breaking each toggle joint, comprising a lever 63, pivoted between its ends to the cylinder frame, as shown at 64, and carrying a weight 65, at its inner end. Pivotally connected with the outer end of each lever 63 is a link 66, the inner end of which is longitudinally slotted, as shown at 67, and this slotted end operates within a strap 68, attached to the lever 54 and to the lever 54'. A pin 69 extends through each lever 54 and 54' and operates within the slot 67.

The operation of the machine is as follows:

The supporting unit, including the cylinders and cylinder frame is rotated counter-clockwise in the direction of the arrow, Figures 3 and 4. This supporting unit is preferably rotated at about 24 R. P. M. The 70 supporting unit is shown in the vertical position, in Figure 3, with toggle joint 54^b, open and toggle joint 54^a closed, the lower piston 29 being in the inner position. When the supporting unit is turned to the left past the vertical position, at an angle of about 45° from the vertical, the lever 63, connected with the toggle joint 54^a, has its outer end moved upwardly by the weight 65, raising lever 54 80 sufficiently, whereby lever 54 and link 57 are drawn out of the straight line position to angular positions, thus breaking the toggle joint, and allowing the weight 62 to shift the toggle joint to the completely open position, shown in Figure 4. The opening of the toggle 85 joint draws the long arm of the shifting lever 39' upwardly, which movement is also aided by the action of the weight 48, due to gravity. When the toggle joint 54^a thus opens or breaks, the toggle 54^b closes, the link 90 57' acting upon the long arm of the shifting lever 39, moving it upwardly, and this movement of the shifting lever 39' is aided by the gravity operated weight 48, connected with its short arm. It is thus seen that the long 95 arms of the shifting levers 39 and 39' are both moved upwardly, in the same direction, thereby shifting the plungers 29 to the opposite ends of the cylinders. The toggle joints 54^a and 54^b remain in this condition 100 until the supporting unit is again turned past the vertical position, shown in Figure 3, at which time the toggle joint 54^a will close while toggle joint 54^b will open and the plungers again shifted to the opposite ends of the cylinders. The movement of the shifting levers 39 and 39' is also aided by the bell crank levers 34 and 34'.

It is to be understood that the form of my invention, herewith shown and described, is to be taken as a preferred example of the same, and that various changes in the shape, size and arrangement of parts, may be resorted to, without departing from the spirit of my invention, or the scope of the subjoined claims.

Having thus described my invention, I claim:

1. In a device of the character described, a rotary support, means mounted thereon, including reciprocating elements, a rod connecting the reciprocating elements, shifting levers pivotally mounted upon the support, a link connected with the rod and the shifting levers, weight carrying levers pivoted upon the support and connected with the shifting levers to move the same, and weight carrying toggle joints pivoted upon the support and connected with the shifting levers.
2. In a device of the character described,

a rotary support, means mounted thereon, including reciprocatory elements, a rod connecting the reciprocatory elements, shifting levers pivoted upon the support, means connecting the shifting levers with the rod, weight carrying levers pivoted upon the support and connected with the shifting levers to move the same, weight carrying toggle joints pivoted upon the support and connected with the shifting levers and weight carrying elements pivoted upon the support and connected with the toggle joints to break the same outwardly.

3. In a device of the character described, a rotary support, means mounted upon the support near its ends, including reciprocatory elements, a rod connecting the reciprocatory elements, shifting levers extending transversely of the support and pivotally connected therewith and having long arms extending in opposite directions, means pivotally connecting such long arms with the rod, weight carrying levers pivotally mounted upon the support and extending upon opposite sides of the same and pivotally connected with the short arms of the shifting levers, toggle joints carrying weights and pivotally connected with the support and extending upon opposite sides of the same and pivotally connected with the long arms of the shifting levers, and automatic means to break the toggle joints outwardly.

4. In a device of the character described, a rotatable support, means mounted upon the same near its ends, including reciprocatory elements, a plunger rod connecting reciprocatory elements, shifting levers pivotally mounted upon the support, each shifting lever having short and long arms, the long arms of the shifting levers extending in opposite directions, a gravity operated element mounted upon the support and connected with the short arm of each shifting lever, toggle joints pivotally mounted upon the support and connected with the long arms of said levers, weights carried by the toggle joints, bell crank levers pivoted upon the support and having their outer arms facing toward the toggle joints, weights carried by said outer arms, links connecting the inner arms of the bell crank levers with the long arms of the shifting levers and means connecting the shifting levers with the rod.

5. In a device of the character described, a rotatable support, means mounted upon the support, including reciprocatory elements, a rod connecting the reciprocatory elements, shifting levers pivoted upon the support, each shifting lever having short and long arms, the long arms extending in opposite directions, a link pivotally connected with the shifting levers and rod, and gravity operated devices mounted upon the support and connected with the long arms of the shifting levers to move the same.

6. In a device of the character described, a rotatable support, means mounted upon the support, including reciprocatory elements, a rod connecting the plungers, shifting levers pivoted upon the support, a link pivotally connected with the rod and shifting levers, and gravity operated devices mounted upon the support and connected with the shifting levers to move the same.

7. In a device of the character described, a rotatable support, means mounted thereon including reciprocatory elements, shifting levers pivoted upon the support and serving to operate the reciprocatory elements, and gravity operated devices carried by the rotatable support and connected with the shifting levers.

8. In a device of the character described, a rotatable support, including reciprocatory elements, means mounted thereon including reciprocatory elements, a shifting lever pivoted upon the support for operating the reciprocatory elements, and a gravity operated device carried by the support and connected with the shifting lever, said gravity operated device including a toggle joint.

9. In a device of the character described, a rotatable support, including reciprocatory elements, means mounted thereon including reciprocatory elements, and a gravity operated toggle joint carried by the support and operating the reciprocatory elements.

10. In a device of the character described, a rotary support, means mounted thereon including a reciprocatory element, a lever pivoted upon the support and having a long arm connected with the reciprocatory element, and a gravity operated device for moving the lever, said device including a gravity operated toggle joint.

In testimony whereof I affix my signature.
FRED A. GERLING.
